MANUFACTURE OF TILE AND BRICK

Filed July 5, 1928

Inventor:

William Hogenson,
or Charles Sherwood,
his Atty.

UNITED STATES PATENT OFFICE

WILLIAM HOGENSON, OF CHICAGO, ILLINOIS, ASSIGNOR TO CHICAGO VITREOUS ENAMEL PRODUCT COMPANY, OF CICERO, ILLINOIS, A CORPORATION OF ILLINOIS

MANUFACTURE OF TILE AND BRICK

Application filed July 5, 1928. Serial No. 290,548.

This invention relates to the manufacture of tile and brick and more particularly to that form of tile and brick composed of vitreous enameled metalware. Tile and brick of this kind are composed of metal pieces shaped to resemble tile or brick and coated with a vitreous enamel which is baked upon the metal and gives it its finished appearance. Ordinarily in the manufacture of such articles, 10 each piece is treated individually, that is to say, each piece of metal forming a tile or brick is handled individually in the process of enameling it.

The principal object of this invention is to 15 reduce the cost of production to a minimum, to save time and labor in the manufacture of the article, and in the packing and shipping thereof. In accordance with the present invention, a length of metal is employed which 20 is formed along its length with a plurality of raised parts simulating tile or brick shaped portions spaced apart from each other by relatively weak or fragile or breakable portions the entire structure being surfaced with vitreous or porcelain enamel baked thereon, 25 whereby the raised portions may be easily separated into individual articles simulating enameled tile, brick, or like articles.

The invention consists in the several novel 30 features hereinafter fully set forth and claimed.

The invention is clearly illustrated in the drawing accompanying this specification in which—

35 Figure 1 is a front elevation of a completed strip embodying a simple form of the present invention;

Fig. 2 is a side elevation thereof looking in the direction of the arrow 2 in Fig. 1;

40 Fig. 3 is a perspective view, upon a larger scale, of a fragment of the strip illustrated in Fig. 1, and showing one of the individual tile or brick detached from the remainder;

Fig. 4 is a perspective view of a fragment 45 of one of the individual tile or brick looking to the rear thereof; and

Fig. 5 is a detail vertical section taken on the line 5—5 of Fig. 1.

50 Referring to the drawing, the reference character 6 designates a vitreous enamel

metal strip having therein a plurality of raised portions or sections 7 simulating tile or brick, spaced apart by narrow webs 8 formed with slots 9 extending crosswise of the strip 6 at places contiguous with the edge portions 10 55 of the raised portions 7. The slots 9 of each series are spaced apart by narrow tongues 11, and said tongues form the immediate connections between the raised portions 7 and the connecting webs 8, and are sufficiently weak 60 or fragile that they may be readily broken by sawing or shearing through them or by bending any section 7 along the series of tongues connecting it with the web 8. The edges 10, above referred to, form the side edges of the 65 raised portions, and the edges 12 form the end edges, thus providing a rectangular article of standard dimensions simulating a tile, brick, or like article of manufacture. The body portion 13 of the strip may be made of 70 sheet metal struck up with suitable dies to form the raised portions, webs and slots, or the body portion may be formed of cast metal.

The metal body portion 13 of the strip, 75 after having been formed as above described, is coated with a vitreous enamel surfacing material 13^a (see Fig. 5) which may be done by dipping the metal strip into a bath containing the vitreous enamel, and, for the purpose, the endmost web 8^a is provided with 80 apertures 14, whereby the strip may be suspended by hooks or other supports. After the vitreous enamel has been applied to the strip, the latter is placed in a suitable furnace and fired or baked. As many coats of vitreous enamel may be applied to the strip as is desired. A vitreous enameled metal strip is thus provided having a plurality of raised sections simulating enameled tile, brick or like articles of manufacture spaced apart by 85 weak or fragile or breakable connecting members. If desired, the strips may be packed in this condition, or the strips may be separated into the individual tiles or brick by breaking, shearing or sawing the individual sections 90 along the weak connecting members, and the individual sections may then be packed for shipment.

It will be observed that with the present manufacture of tile or brick, the separate 100

handling of the individual tile pieces, not only in the formation of the body portion thereof, but in the coating and enameling process, is eliminated, and that a large number of connected articles may be handled at a time as one piece, thereby greatly lessening the cost of production, as well as the time and labor required in the production of the article. The body portion being made of thin metal coated with vitreous enamel, the articles are extremely light and may be easily handled in applying them to the surface upon which they are used.

It will be understood that the size or shape of the struck up portions is immaterial, and that they may be given any suitable or desired configuration. Furthermore, that the articles may be used in the various situations where articles of a similar nature have been heretofore used, as, for instance, on walls, ceilings, floors and the like.

More or less variations of the exact details of construction is possible without departing from the spirit of this invention. I desire, therefore, not to limit myself to the exact form of the construction shown and described, but intend, in the following claims, to point out all of the invention disclosed herein.

I claim as new, and desire to secure by Letters Patent:

1. A metal strip for use in the manufacture of tile and brick articles, said strip having spaced raised portions simulating tile or brick and connected at the bottoms of the raised portions by relatively weak connecting members, the entire strip being provided with a surface portion composed of vitreous enamel.

2. A metal strip for use in the manufacture of tile or brick articles, said strip having struck up portions simulating tile or brick spaced apart by webs formed integral therewith, the adjacent bottom edges of the struck up portions and webs being separated by slots and connected by fragile tongues.

WILLIAM HOGENSON.
